UNITED STATES PATENT OFFICE.

THEODORE W. FOSTER, OF PROVIDENCE, RHODE ISLAND, ASSIGNOR TO THEODORE W. FOSTER & BRO. CO., OF PROVIDENCE, RHODE ISLAND, A CORPORATION OF MAINE.

DESIGN FOR A HANDLE FOR TOILET AND MANICURE IMPLEMENTS OR SIMILAR ARTICLES.

Application filed May 11, 1922. Serial No. 2,195. Term of patent 3½ years.

To all whom it may concern:

Be it known that I, THEODORE W. FOSTER, a citizen of the United States, residing at the city of Providence, county of Providence, State of Rhode Island, have invented a new, original, and ornamental Design for a Handle for Toilet and Manicure Implements or Similar Articles, of which the following is a specification, reference being had to the accompanying drawing, forming a part thereof.

The figure is a face view of a handle for toilet and manicure implements or similar articles, illustrating my new design.

I claim:

The ornamental design for a handle for toilet and manicure implements or similar articles, as shown.

THEODORE W. FOSTER.
